222,891

VEHICLE SIGNAL LAMP OR THE LIKE

Leandre Proteau, 791 Decelles Terrace, Jacques
Cartier, Quebec, Canada

Filed June 1, 1970, Ser. No. 23,219

Term of patent 14 years

Int. Cl. D26—06, 05

U.S. Cl. D48—32

Fig. 1

Fig. 2

Fig. 3

Fig. 4

Fig. 5

FIG. 1 is a side elevational view of the vehicle signal lamp or the like showing my new design;

FIG. 2 is a bottom plan view thereof;

FIG. 3 is a top plan view thereof;

FIG. 4 is an end elevational view as seen from the left of FIG. 3, being fragmentarily shown for convenience of illustration;

FIG. 5 is an end elevational view as seen from the right of FIG. 3.

I claim:

The ornamental design for vehicle signal lamp or the like, shown and described.
